United States Patent Office.

HUGH H. CRAIGIE, OF NEW YORK, N. Y.

Letters Patent No. 66,920, dated July 2, 1867.

IMPROVEMENT IN SINKS.

The Schedule referred to in these Letters Patent and making part of the same.

TO ALL WHOM IT MAY CONCERN:

Be it known that I, HUGH H. CRAIGIE, of the city and State of New York, have invented, made, and applied to use a certain new and useful Improvement in Sinks; and I do hereby declare the following to be a full, clear, and exact description of the said invention, reference being had to the annexed drawing, making part of this specification, wherein—

Figure 1 is an inverted plan of the sink; and

Figure 2 is a vertical section at the line x x , showing the trap and pipe.

Similar letters denote the same parts.

Sinks have heretofore been formed with a bent pipe to retain water and form a trap to the sewer pipe. This is liable to become choked, and, being of necessity some little distance below the sink, is liable to injury from pails, pots, or other kitchen utensils that are often placed in a closet that is formed under the sink. In making the attachment between the iron ferrule and the lead pipe a flange with bolts and nuts has usually been employed; but this device is costly and unsightly.

The nature of my said invention consists in a trap formed by a cup attached to the under side of the sink, into which a ferrule from the sink passes, and terminates below the water line in said cup. The escape pipe passes off from the side of this cup in the form of a bend, so that the pipe to the sewer can be vertical and close against the wall; and I unite the iron and lead pipe by dressing the soft-metal pipe into a contraction or neck in the iron pipe and driving over it a metal ring, which makes a very strong, tight, and neat joint, because the neck receiving the soft-metal pipe prevents the joint becoming loose by concussion or strain, because the pipe cannot draw off said neck; neither can the iron pipe slide further into the lead pipe, the neck holding the pipes together, and preventing a movement in either direction.

In the drawing, a represents the sink, of any desired size or shape; b is a ferrule formed below the grating or strainer c , and d is the cup forming the trap. This cup is attached to the under side of the sink by means of wedge-shaped lugs e entering between lips or projections upon the under side of the sink. f is the bend passing off from the side of the cup d , and terminating near the back of the sink, so that the pipe g , leading to a cesspool or sewer, may stand vertically, or nearly so, against the wall or support against which the sink is placed. The pipe g is attached to the iron pipe f by the said pipe f being entered within the end of the pipe g , the ring h being first slipped on. The soft-metal pipe g is then hammered or pressed down into a recess or neck, i , around the end of the pipe f ; and the ring h , driven over the end of the pipe g , secures the parts firmly and tightly together.

What I claim, and desire to secure by Letters Patent, is—

1. A trap for sinks, formed by the detachable cup d , attached to the under side of the sink, in combination with the downward-projecting ferrule or pipe b , as and for the purposes set forth.
2. I claim the bend f and trap d , in combination with the soft-metal pipe g , connected to the bend f by the ring h and neck, substantially as and for the purposes set forth.

In witness whereof I have hereunto set my signature this 19th day of January, A. D. 1867.

HUGH H. CRAIGIE.
